PANTIES WITH SHAPE-RETAINING CUFFS

Howard B. Snader, Temple, Pa., assignor to Vanity Fair Silk Mills, Reading, Pa., a corporation of Pennsylvania

Application July 10, 1936, Serial No. 90,674

6 Claims. (Cl. 2—224)

This invention relates to the class of apparel and particularly to women's knit pants.

The general object of the invention is to provide an article of the type described having relatively elastic cuffs fitting resiliently against the leg, in which the original elasticity is perpetuated throughout the life of the garment.

Ordinarily the knit fabric becomes permanently stretched through being worn, from the heat of the body, laundering, etc., so that the cuffs become loose and distorted and do not fit the leg closely.

The present invention obviates this defect by providing a cuff of knit fabric lined with an adherent film of rubber solution which fortifies the native elasticity of the fabric preventing it acquiring a set when stretched, so that it invariably reassumes its original shape when released from stretching.

Another object of the invention is the construction of knit fabric panties having the wales of the knitting in the cuff substantially perpendicular to the circumference of the cuff, and treated for example, by spraying with a film of rubber or the like so thin and intimately adhesive that it does not bridge the wales, but follows the undulations of the wales and between them, forming in effect a mechanical spring which pulls the wales back to their original close spacing after the fabric has been released from stretching, preventing a permanent set or stretched condition of the cuff portion of the garment.

Still another object of the invention is the construction of the cuff portion from a folded piece of knit fabric with the wales running perpendicular to the circumference and the inside faces coated with a film of rubber which follows the undulations of the wales as described and possesses residual tackiness so that the two plies constituting the cuff become united and doubly effective in restoring the cuff to its original size and shape.

The invention is as well adapted to the waistband of the apparel as the limb cuffs.

Other objects of the invention will appear as the following description of a preferred and practical embodiment thereof proceeds.

In the drawing which accompanies and forms a part of the following specification and throughout the several figures of which the same characters of reference have been employed to designate identical parts:

Figure 1 is a perspective view of a garment illustrating my invention, displayed on a figure;

Figure 2 is a section through the cuff and the adjacent body portion of the garment;

Figure 3 is a perspective view of a fragment of the cuff portion in flat or unfolded state.

Referring now in detail to the several figures, the numeral 1 represents the garment forming the subject of the invention which may be of any style and any material, the only prerequisite being that it be of knit material and therefore elastic particularly in the cuff portions 2 which are designed to fit the legs snugly, however, without any binding or garter effect. The cuff portions 2 may be knit of the same material as the body portion of the garment 1 in fact insofar as the invention is concerned they may be integral therewith, although it is preferred to make them separately and stitch them to the body portion.

It is one of the shortcomings of knit pants of the type which are designed to fit the leg closely that the requisite elasticity is short-lived and that almost as soon as the garment is worn, the cuff portions become permanently stretched and will not reassume the original size or shape, but hang loosely around the leg in an uncomfortable and unsightly manner.

I have found that if the material in the cuff portion be treated on the unexposed side by a spray of latex or other suitable rubber solution so as to deposit a thin film of rubber on the unexposed side, such cuff portions after vulcanization will not become distorted through stretching or other causes, but possess enough inherent elasticity to return to their original shape when the stretching cause has been removed.

In Figure 3 the preferred manner of carrying out the invention is shown, the numeral 3 representing a strip of knit fabric, the same fabric preferably of which the body portion 1 is made. This strip has a sprayed film 4 of latex or other suitable rubber solution. After the film has been vulcanized, the strip 3 is folded along the line 5, which line becomes the bottom edge of the leg opening. The two plies 6 and 7 formed by the folding are brought together in the manner illustrated in Figure 2 and stitched around the leg opening of the garment as illustrated at 8 in Figure 2. The film material which as stated may be latex rubber has a small degree of residual adhesiveness even for a long period of time after its manufacture which causes the films on the opposite sides of the fold to unite where they touch, welding the two plies of fabric into a unitary structure. The rubber film being on the inside of the hem does not interfere with the dyeing of the material so that it may be dyed optionally be-

fore or after having been treated with the rubber solution.

In the preferred embodiment of my invention, the knitting of the strip 3 is of such character as to produce closely adjacent wales 9 extending perpendicularly with respect to the circumference of the cuff opening, the wales appearing upon the inside as well as the outside of the fabric. The adhesive film which is preferably sprayed is of such thinness and intimate adhesiveness as to follow the contour of the wales making the film closely undulating as illustrated at 10 in Figure 3. This in effect makes the film function in the same manner as a mechanical spring, adding to the inherent resiliency of the rubber, the elasticity produced by the flattening and bowing of the undulations of the film as the fabric is stretched and relaxed. This greatly enhances the coefficient of resiliency of the cuff and assures that the cuff will be restored to its original shape and size after having been released from stretching. The uniting of the two plies of the hem through the residual tackiness of the rubber film doubles the elastic capacity of the hem since the front and back plies cannot act separately, but must stretch and contract together.

In the event that the material is such that the wales are closely spaced, a convenient method of carrying out the invention is to apply the coating while the material is stretched so as to cause it to follow the undulations of the wales, then to release the material and to vulcanize the coating or film while the material is in relaxed condition.

35 While I have in the above description disclosed what I believe to be a preferred and practical embodiment of the invention, it will be obvious to those skilled in the art that the details of construction as well as the style of the garment or 40 the material of which it is made are immaterial to the invention, the scope of which is to be determined by a fair interpretation of the appended claims.

What I claim is:

45 1. Women's pants of knit material formed with circumferential openings, the material bounding said openings finished with attached circumferential knit terminal hem having wales extending perpendicular to the circumference of the hem, 50 each hem comprising a strip of knit material coated on one side with a thin film of rubber or the like set in undulating form following the sur-

face of the wales and the depressions between the wales, said material being folded with said film on the unexposed surface.

2. Article of apparel of knit material formed with a circumferential hole, the material being formed with a knit hem bounding said hole having wales perpendicular to the circumferential dimension of said hem, the hem being coated on one side with a thin film of elastic rubber having a set shape acquired in situ while the fabric of 10 the hem was in an unstretched condition.

3. Article of apparel of knit material formed with a circumferential hole, the material being formed with a folded knit hem bounding said hole, having wales perpendicular to the circumferential dimension of said hem, the unexposed face only of the hem being coated with a thin film of elastic rubber having a set shape acquired in situ while the fabric of the hem was in unstretched condition and by means of which film 20 the two plies of the hem are adhesively united.

4. Article of apparel of knit material formed with a circumferential hole, the material being formed with a knit hem bounding said hole, having wales running perpendicular to the circumference of the hem, and a thin coating of rubber on the side of said hem following the undulations of the wales, the elasticity of the rubber dominating that of the basic fabric of the hem.

5. Article of apparel of knit material formed with a circumferential hole, the material being formed with a folded knit hem bounding said hole, having wales running perpendicular to the circumference of the hem, the inside face only of the hem being coated with a thin film of elastic rubber following the undulations of the wales, said film having a set shape acquired in situ while the fabric of the hem was in unstretched condition.

6. Method of making shape-retaining articles 40 of apparel of knit material of that type having circumferential holes in which the material is formed with knit hem bounding said holes, comprising tensioning the hem portions, applying a coating of rubber or its equivalent to the wales 45 and valleys between the wales in a film on one side of said hem portions, releasing said hem portions so that said film assumes an undulating shape, and vulcanizing said film with the hem in released condition, thereby giving the film a set 50 repose shape of undulating form when contracted.

HOWARD B. SNADER.
